UNITED STATES PATENT OFFICE.

ELLIS S. OLIVER, OF NEWARK, NEW JERSEY.

SOUND-MODIFYING MEANS FOR TALKING-MACHINES.

932,055.

Specification of Letters Patent. Patented Aug. 24, 1909.

Application filed October 31, 1907. Serial No. 400,113.

To all whom it may concern:

Be it known that I, ELLIS S. OLIVER, a citizen of the United States, residing at Newark, in the county of Essex and State 5 of New Jersey, have invented certain new and useful Improvements in Sound-Modifying Means for Talking-Machines; and I do hereby declare the following to be a full, clear, and exact description of the invention, 10 such as will enable others skilled in the art to which it appertains to make and use the same, reference being had to the accompanying drawings, and to characters of reference marked thereon, which form a part of this 15 specification.

This invention has reference, generally, to improvements in talking machines and similar sound-reproducing machines, such as the graphophone and the phonograph; and, the 20 present invention relates more particularly to a novel means for use with the usual sound-conveying member leading to the reproducing horn, said means being for the purposes of modifying the sounds and by 25 means of the mechanism varying to any desired extent the degree of the reproduced sounds.

This invention therefore has for its principal object to provide a simply constructed 30 and efficiently operating sound-modifying means for use with the sound-conveying tube or member of the various forms of talking machines, which is under perfect control of the operator and can be most easily worked, 35 so that the sounds can be reproduced with modified effects, and especially is this so with the reproduction of musical sounds, as the singing of a person, or a piece played upon a musical instrument or instruments, the 40 pianissimo and forte effects being most perfectly reproduced.

Other objects of this invention not at this time more particularly enumerated will be clearly understood from the following detailed description of my present invention. 45

The invention consists, primarily, in the novel sound-modifying device for use with talking machines of the various kinds; and the invention consists, furthermore, in the 50 general arrangements and combinations of devices and parts, as well as in the details of the construction of the same, all of which will be hereinafter more fully described, and

then finally embodied in the clauses of the claims which are appended to and which 55 form an essential part of this specification.

The invention is clearly illustrated in the accompanying drawings, in which:

Figure 1 is a side elevation of one form of talking machine and its sound-conveying 60 tube or member leading to the sound-reproducing horn, a portion of which is shown in elevation, said view showing also in end-elevation the button or operating-member of the sound-modifying means used with said 65 tube. Fig. 2 is an enlarged view of said sound-conveying tube or member, shown partly in plan and partly in horizontal section, with an end-portion of the sound-modifying means shown in top view. Fig. 3 is a 70 horizontal sectional representation of the jointed elements of said sound-conveying tube or member, with the sound-modifying means shown in plan within the joint of said elements; and Fig. 4 is a horizontal section, 75 made on an enlarged scale, of said jointed elements, and of the sound-modifying means arranged in said joint, showing one general arrangement of the parts comprising said sound-modifying means. Fig. 5 is a vertical 80 section taken on line 5—5 in said Fig. 4, but made on a still larger scale, said section showing the sound-modifying means in its wide-open position within the jointed elements of the sound-conveying tube or member; and Figs. 6 and 7 are similar sectional 85 representations of the same parts, but showing the sound-modifying means in two of its other positions for modifying the sound.

Similar characters of reference are employed in all of the above described views, to indicate corresponding parts.

Referring now more particularly to Figs. 1 to 7 inclusive, the reference-character 1 indicates one form of talking machine of the graphophone-type, and 2 is the usual suitable support connected with and extending in an upward direction from the casing or box of the machine, said support being provided with a supporting means, as 3, for the usual 95 sound-reproducing horn 4. Extending from and rotatably connected with said supporting means 3 is the usual sound-conveying tubular member 5 which is provided at its end-portion 6 with a horizontally disposed tubular sleeve-like member 7, said member being 100 105

open at both ends and establishing communication with the inner tubular portion of and then terminating in a substantially semi-cylindrical part 27 of substantially the

same, as set forth in the detailed description of my present invention.

I claim:—

1. In combination with a sound-conveying tube of a talking machine, a tubular sound-modifying means within said tube which is longitudinally divided, so as to provide a longitudinally extending open part. 5
2. In combination with a sound-conveying tube of a talking machine, an oscillatory tubular sound-modifying means within said tube which is longitudinally divided, so as to provide a longitudinally extending open part. 10
3. In combination with a flexible sound-conveying tube of a talking machine, a tubular sound-modifying means within said tube, which is longitudinally divided, so as to provide a longitudinally extending open part. 15
4. In combination with a flexible sound-conveying tube of a talking machine, an oscillatory tubular sound-modifying means within said tube which is longitudinally divided, so as to provide a longitudinally extending open part. 20
5. In combination with a sound-conveying tube of a talking machine, a tubular sound-modifying means within said tube which is longitudinally divided, so as to provide a longitudinally extending open part, and a finger-piece extending from said modifying means to a point upon the outside of the sound-conveying tube. 25
6. In combination with a sound-conveying tube of a talking machine, an oscillatory tubular sound-modifying means within said tube which is longitudinally divided, so as to provide a longitudinally extending open part, and a finger-piece extending from said modifying means to a point upon the outside of the sound-conveying tube for oscillating the said modifying means. 30
7. In combination with a flexible sound-conveying tube of a talking machine, a tubular sound-modifying means within said tube which is longitudinally divided, so as to provide a longitudinally extending open part, and a finger-piece extending from said modifying means to a point upon the outside of the sound-conveying tube. 35
8. In combination with a flexible sound-conveying tube of a talking machine, an oscillatory tubular sound-modifying means within said tube which is longitudinally divided, so as to provide a longitudinally extending open part, and a finger-piece extending from said modifying means to a point upon the outside of the sound-conveying tube for oscillating the said modifying means. 40
9. In combination with a sound-conveying tube of a talking machine, a sound-modifying means within said tube comprising an element arranged in said tube and provided with a tubular part, a stem rotatably arranged in the tubular part of said element, 45

said stem being provided upon one end with a finger-piece and having its other end-portion extending beyond said element and into said sound-conveying tube, and a valve-like member upon said end-portion of the stem. 70

10. In combination with a sound-conveying tube of a talking machine, a sound-modifying means within said tube comprising an element arranged in said tube and provided with a tubular part, a stem rotatably arranged in the tubular part of said element, 75 said stem being provided upon one end with a finger-piece and having its other end-portion extending beyond said element and into said sound-conveying tube, and a valve-like member upon said end-portion of the stem, consisting of a straight-portion adapted to be secured upon said stem, and a curved spring-part extending from said straight-portion in slidable contact with the inner surface-portion of the sound-conveying tube. 80

11. In combination with a sound-conveying tube of a talking machine, a sound-modifying means within said tube comprising an element arranged in said tube and provided with a tubular part, a stem rotatably arranged in the tubular part of said element, 85 said stem being provided upon one end with a finger-piece and having its other end-portion extending beyond said element and into said sound-conveying tube, and a valve-like member upon said end-portion of the stem, consisting of a straight-portion adapted to be secured upon said stem, and a curved spring-part extending from said straight-portion in 90 slidable contact with the inner surface-portion of the sound-conveying tube, substantially as and for the purposes set forth. 95

12. In combination with a sound-conveying tube of a talking machine, said tube being provided with an internally screw-threaded portion, a sound-modifying means within said tube comprising a screw-threaded element 100 adapted to be screwed into the screw-threaded portion of said sound-conveying tube, and said element being provided with a tubular part, a stem rotatably arranged in the tubular part of said element, said stem being provided upon one end with a fingerpiece and having its other end-portion extending beyond said element and into said sound-conveying tube, and a valve-like member upon said end-portion of the stem. 105

13. In combination with a sound-conveying tube of a talking machine, said tube being provided with an internally screw-threaded portion, a sound-modifying means within said tube comprising a screw-threaded element 110 adapted to be screwed into the screw-threaded portion of said sound-conveying tube, and said element being provided with a tubular part, a stem rotatably arranged in the tubular part of said element, said stem being provided upon one end with a finger-piece and having its other end-portion extending beyond said element and into said sound-conveying tube, and a valve-like member upon said end-portion of the stem. 115

120

125

130

being provided upon one end with a finger-piece and having its other end-portion extending beyond said element and into said sound - conveying tube, and a valve - like member upon said end-portion of the stem, consisting of a straight-portion adapted to be secured upon said stem, and a curved spring-part extending from said straight-portion in 5 slidable contact with the inner surface-portion 10 of the sound conveying tube.

14. In combination with a sound-conveying tube of a talking machine, said tube being provided with an internally screw-threaded portion, a sound-modifying means within 15 said tube comprising a screw-threaded element adapted to be screwed into the screw-threaded portion of said sound-conveying tube, and said element being provided with a tubular part, a stem rotatably arranged 20 in the tubular part of said element, said stem being provided upon one end with a finger-piece and having its other end-portion extending beyond said element and into said sound - conveying tube, and a valve - like 25 member upon said end-portion of the stem, consisting of a straight-portion adapted to be secured upon said stem, and a curved spring-part extending from said straight-portion, and a soft fabric secured upon said spring-30 part, said fabric being in slidable contact with the inner surface-portion of the sound-conveying tube, substantially as and for the purposes set forth.

15. In combination with a sound-conveying tube of a talking machine, comprising a 35 pair of flexibly connected tubular members, one of said members being arranged within the other member and being provided with a retaining shoulder and having an internally 40 screw-threaded portion, a sound-modifying means within said inner member, said modifying means comprising a screw-threaded element adapted to be screwed into the screw-threaded portion of said inner member, and said element being provided with a 45 tubular part, a stem rotatably arranged in the tubular part of said element, said stem being provided upon one end with a finger-piece and having its other end-portion extending beyond said element and into said 50 sound - conveying tube, and a valve - like member upon said end-portion of the stem,

16. In combination with a sound-conveying tube of a talking machine, comprising a 55 pair of flexibly connected tubular members,

one of said members being arranged within the other member and being provided with a retaining shoulder and having an internally screw-threaded portion, a sound-modifying means within the inner member, said 60 modifying means comprising a screw-threaded element adapted to be screwed into the screw-threaded portion of said inner member, and said element being provided with a tubular part, a stem rotatably arranged in 65 the tubular part of said element, said stem being provided upon one end with a finger-piece and having its other end-portion extending beyond said element and into said sound - conveying tube, and a valve - like 70 member upon said end-portion of the stem, consisting of a straight-portion adapted to be secured upon said stem, and a curved spring-part extending from said straight-portion in 75 slidable contact with the inner surface-portion of the sound conveying tube.

17. In combination with a sound-conveying tube of a talking machine, comprising a pair of flexibly connected tubular members, one of said members being arranged within the other member and being provided with a retaining shoulder and having an internally 80 screw-threaded portion, a sound-modifying means within the inner member, said modifying means comprising a screw-threaded element adapted to be screwed into the screw-threaded portion of said inner member, and said element being provided with a tubular part, a stem rotatably arranged in the tubular part of said element, said stem 85 being provided upon one end with a finger-piece and having its other end-portion extending beyond said element and into said sound - conveying tube, and a valve - like member upon said end-portion of the stem, consisting of a straight-portion adapted to be 90 secured upon said stem, and a curved spring-part extending from said straight-portion and a soft fabric secured upon said spring-part, said fabric being in slidable contact 95 with the inner surface-portion of the sound-conveying tube, substantially as and for the purposes set forth.

In testimony, that I claim the invention set forth above I have hereunto set my hand 100 this 29th day of October, 1907.

ELLIS S. OLIVER.
